UNITED STATES PATENT OFFICE.

MARIAN F. ADKINS, OF RANGER, WEST VIRGINIA.

FRAMING-TOOL.

1,039,076.

Specification of Letters Patent. Patented Sept. 24, 1912.

Application filed November 9, 1909. Serial No. 527,006.

To all whom it may concern:

Be it known that I, MARIAN F. ADKINS, a citizen of the United States, residing at Ranger, in the county of Lincoln and State 5 of West Virginia, have invented certain new and useful Improvements in Framing-Tools; and I do hereby declare the following to be a full, clear, and exact description of the invention, such as will enable others skilled 10 in the art to which it appertains to make and use the same.

My invention relates to new and useful improvements in framing tools and especially to the class used for measuring in 15 connection with the pitch and slope of roofs and an object of my device is to provide a tool having a scale for determining the angles of the frame-work used in constructing a roof.

20 A further object of my device is to provide a compact form which may be readily carried in a carpenter's chest and a still further object is to provide a device which may be utilized to determine bevels and 25 angles.

A still further object is to provide a device having a previously calculated scale so arranged as to be within sight of the operator at all times.

30 These and other objects will be more particularly referred to in the following specification and claims.

In the accompanying drawings forming a 35 part of this application, Figure 1 is a top plan view showing the various working parts of the tool, and, Fig. 2 is a transverse section taken on the line 2-2 of Fig. 1.

Referring to the drawings in which similar reference numerals designate corresponding parts throughout the several views, 1 is what may be termed as the handle 40 of my device consisting of plates 2 and 3 made of any preferred material such as wood, metal, or the like, and secured together along their edges at a right angle to each other. Along the outer face of each 45 of the said plates 2 and 3, respectively, are tables of conversion factors 4 and 5, the purpose of which will be hereinafter more particularly described.

50 One end of each of the plates 2 and 3 is bifurcated to form slots 6 and 7, respectively, the slot 6 being adapted to receive an arm 8, while the slot 7 is likewise adapted to receive a similar arm 9, said arms having scales marked on one edge thereof. The

arms 8 and 9 are pivotally secured in each of the said slots 6 and 7 by means of the thumb screws 10 and 11, said thumb screws not only forming a pivot for each of the 60 arms, but also securing them firmly in engagement with the plates 2 and 3. The arms 9 and 8 are pivotally secured to brace rods 12 and 13, respectively, the other ends of said brace rods being secured to indicating slides 14 and 15, respectively. When not in use, the arms and brace rods may be moved into the channels 6 and 7 provided in the plates 2 and 3, respectively. The indicating slides 14 and 15 are secured to the 70 brace rods 12 and 13, respectively, by means of thumb screws 16 and 17, said slides being adapted to move longitudinally in the channels 18 and 19 which extend substantially one-half the length of each of the plate 75 members.

The scale 4, by means of which the lengths of the various rafters are determined, includes both angles of the handle, and extends from one end to about midway the 80 length of the handle. The scale 5 also includes both angles of the handle. This last scale, however, is divided or duplicated, being the same upon each angle. The scale 5 is used for determining the cuts of the 85 ends of the rafters, as will later be more clearly understood.

It being understood that the width of the building is known and also the desired pitch of the roof, the scale 4 is used in the following manner: A is the pitch of the roof running from two inches rise to the foot run, to and including sixteen inches to the foot run and is represented by the figures 2, 3, 4, 5, etc., until the desired number is reached 95 (the highest number in the illustration being 9.)

B is the length of common rafters. The proper figure upon this scale multiplied by one-half the width of the building (whatever the width of the building may be) will give the length of the common rafters.

C is the length of hip or valley rafters, this scale being indicated by the letters LHV. These figures multiplied by half the 105 width of the building, the same as in determining the length of the common rafters, will give the length of the hip or valley rafters.

D is a scale for determining the length of 110 the first jack or cripple rafter, spaced sixteen inches on centers, and is indicated by

the letters LFJ. The figures of this scale representing the exact length of the first jack rafter for the different rises of roof, the rafter to be spaced sixteen inches on centers.

5 E is a scale for determining the length of the first jack or cripple rafter spaced two feet on centers and is marked by the letters LFJ, same as the previous scale and also 10 read in the same manner.

By means of the scale 5, previously mentioned, the different cuts of all rafters in a roof running from two inches rise to the foot run, to and including sixteen inches 15 rise to the foot run, may be readily determined, as will now be described.

The plumb cuts for common rafters for the sixteen different pitches of roof may be readily determined upon the row of figures 20 marked F by raising the arm to correspond with the mark representing the pitch of roof desired, as will be clearly understood, this row of figures being marked PC, which means plumb cut of common rafters.

25 G is a row of figures for determining the foot cut of common rafters. By raising the arm to correspond with the mark giving the pitch desired, the proper cut will be indicated on the row of figures G, which row 30 of figures is designated by the letters FC.

H represents the plumb cut for hip or valley rafters. By raising the arm to correspond with the mark representing the pitch of roof desired, the indicating slide 35 connected with the arm will point to the numbers representing the plumb cut for the hip or valley rafters. The row of figures representing the various plumb cuts is marked PHV.

40 I represents the foot cut of hip or valley rafters. By raising the arm corresponding to the pitch of roof desired, the foot cut of hip or valley rafters will be indicated upon the row of figures marked FHV.

45 J represents the row of figures for determining the side cut of jack rafter, which side cut is indicated by raising either arm of the two to correspond with the mark representing the pitch of roof desired. This 50 row of figures is marked SJ, which means side cut of jack or cripple rafter.

It will be understood that the inner edges of the braces 12 and 13 point to and indicate the pitch of the roof, the positions and 55 angles of the braces being varied by swinging the arms 9 and 8, respectively, upon their pivots.

Describing more fully the operation and 60 use of the scale 5, we will take for example an eight pitch roof, which is the pitch more commonly employed. We understand that the plumb cut of common rafter will also give the plumb cut of jack or cripple rafter. First we will raise one arm of the tool to 65 correspond with mark 8, giving plumb cut

of common rafter. Now we have the plumb cut for the jack rafter. Next we will raise the other arm of the tool to correspond with the mark 8 representing the side cut of jack rafter. The tool is then placed on the timber to be cut, with the plates 2 and 3 each against a side thereof, the timber marked along the outer edge of the first arm to indicate the plumb cut, and along the outer edge of the second arm to indicate the side cut of the jack rafter. Either arm of the tool may then be raised to correspond with the mark for obtaining the foot cut of the rafter, the tool reversed and the timber marked along the outer edge of the arm to indicate the foot cut of the jack rafter, as will be clearly understood. The raising of either arm to determine the various cuts is possible on account of the scale 5 being the same upon both angles of the tool.

85 It will be understood that when the tool is in position on the timber, the latter may be readily marked for the various cuts by drawing a pencil or the like along the outer edges of the adjusted arms 8 and 9.

In obtaining the various adjustments of the arms, braces and indicating slides, the latter, as will be understood, are moved backwardly or forwardly along the channels 18 and 19, respectively, the thumb 95 screws 16 and 17 being tightened when the slides are in the proper positions.

The manner of locating the arms 8 and 9 permit the tool to be used as a square or a bevel. It is therefore seen that the possibilities of the various uses to which this tool may be put are many in number and, inasmuch as it is a compact device and readily adapted to the various requirements in constructing roofs or the like, persons 100 having need for such a device will no doubt appreciate its value.

From the above description it will be appreciated that a simple, inexpensive article having a wide range of utility, has been 110 provided.

What I claim is:

1. The herein described device, comprising the combination with a handle composed of two plates secured together along 115 their edges at a right angle to each other and each having a slot in one end thereof; of a pair of arms pivotally secured in said slots and adapted to rotate therein, means to fixedly secure each of said arms in their 120 adjusted positions, brace rods, one end of each of said brace rods being pivotally secured near the pivotal ends of said arms, the other end of each of said brace rods being pivotally secured to an indicating means, 125 said plates having channels therein, said indicating means being engaged and adapted to slide in said channels and a scale on said plates cooperating with the said indicating means.

2. In a new article of manufacture, a pair of plates positioned at right angles to each other, each of said plates having a slot therein, a pair of arms pivotally secured 5 and adapted to rotate one in each of said slots, means for securing said arms in fixed relation to each of said corresponding plates, a brace rod pivotally secured to one edge of each of said arms, the opposite edge 10 thereof being marked with a scale, each of said plates having a channel extending longitudinally from one end thereof substantially half the length thereof, indicating slides designed to move laterally one in each 15 of the said channels, the free end of each of said brace rods being pivotally secured to one of the said slides whereby each of
- 20 said arms may be raised at an angle to its respective plate, scales upon the outer faces of the plates along the channeled ends thereof, said indicating slides being adapted to move over the last mentioned scales to determine the cuts of rafters, and a rafter length determining scale upon the outer faces of the plates at the adjacent ends of 25 said plates.

In testimony whereof I have signed my name to this specification in the presence of two subscribing witnesses.

MARIAN F. ADKINS.
